US0D1099447S

(12) **United States Design Patent** (10) **Patent No.:** **US D1,099,447 S**
(45) **Date of Patent:** **** Oct. 21, 2025**

(54) **VACUUM**

(71) Applicant: **DaVinci II CSJ, LLC**, Fairfield, NJ (US)

(72) Inventors: **Ajit Khubani**, Fairfield, NJ (US); **Mohan Rajasekaran**, Watertown, CT (US)

(73) Assignee: **DaVinci II CSJ, LLC**, Fairfield, NJ (US)

(**) Term: **15 Years**

(21) Appl. No.: **29/933,392**

(22) Filed: **Mar. 19, 2024**

(51) **LOC (15) Cl.** **15-05**

(52) **U.S. Cl.**

USPC **D32/18**

(58) **Field of Classification Search**

USPC D15/199; D21/526, 578; D32/15, 17, D32/18, 21

(57) **CLAIM**

The ornamental design for a vacuum as shown and described.

DESCRIPTION

FIG. 1 is a front right perspective view of a vacuum in accordance with the present invention;

FIG. 2 is a rear left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawing depict portions of the vacuum that form no part of the claimed design.

1 Claim, 7 Drawing Sheets
